UNITED STATES PATENT OFFICE

JAY G. ROBINSON, OF CHICAGO, ILLINOIS

FIRE-BOX DOOR

Application filed July 29, 1929. Serial No. 381,763.

My invention is an improvement in power operated fire-box doors such as are now in use upon locomotives. The improvement relates more particularly to the type of apparatus described and illustrated in my co-pending application for patent upon an improvement in fire box doors, Ser. No. 380,117, filed July 22, 1929. In said co-pending application I have described the invention therein claimed in its application to two types of fire-box doors which are now in use and known respectively as the Shoemaker door and the Franklin door, to both of which types of door the invention herein described is in its broad aspect also applicable.

In the drawings.

Figure 1 is a face view of a locomotive fire-box door of the Shoemaker type with my invention applied thereto, parts being shown in section to more clearly exhibit the structure and operation.

Figure 2 is an enlarged detail view in elevation and partly in section showing the construction of an operating valve or pet cock.

Figure 3 is a sectional view still further enlarged of the plug of the pet cock.

Figure 4 is a view partly in horizontal section showing the parts to which the invention is directly applied.

Figure 5 is a perspective view of a modified form of a plunger which forms part of the structure and Figures 6, 7 and 8 are longitudinal and transverse sections showing the modified plunger and its cooperating sleeve, Figures 7 and 8 being sections on line A—A of Figure 6.

Referring first to Figure 1 of the drawings, a door ring or frame 1 is secured to the boiler end around the door opening, and doors 2 and 3, meeting when closed on line 4, are pivoted at 5 and 6 to the door ring. The pneumatic door operating motor comprises a differential cylinder 7 and cooperating large and small rigidly connected pistons 8 and 9. The piston rod is pivotally connected at 12 to lever 11, which latter is pivotally connected at 13 and 14 to levers 15 and 16 respectively. The levers 15 and

16 are pivotally mounted on the door frame at 17 and 18 respectively and at their inner ends have pivotal connection at 19 and 20 with links 21 and 22 respectively and the opposite ends of said links are pivotally connected to doors 3 and 2 at 23 and 24 respectively. It will be apparent that downward movement of the piston rod 10 will through the connections above described open the doors and that its reverse movement will close them.

By means of a treadle 25 a valve 26 may be actuated to establish and cut off communication between the main air reservoir on the locomotive, not shown, and the port 27 leading to the space above the large piston 8. The space between the large and small pistons, designated 30, is normally in communication with the main air reservoir through the port 28 and passage 31, a check valve 29 being provided to prevent flow of air toward the reservoir through said passage. A two-way valve 32 is provided in the passage 31, which valve in the position shown in Figures 1 and 3 permits the communication above referred to between the main reservoir and space 30 between the pistons. The valve 32 may be manually turned by endwise movement of rod 33 which is pivotally connected to the arm 34, the latter arm being rigidly fixed to the plug of valve 32. When valve 32 is turned to the position shown in Figure 2 the space 30 is cut off from communication with the main air reservoir and is placed in communication with the atmosphere through port 35 thus substituting atmospheric pressure for reservoir pressure between the pistons.

In the normal position of the parts, with the doors closed, valve 32 is in the position shown in Figure 1 with reservoir pressure between the pistons and atmospheric pressure in the space above the large piston 8 which space is then in communication with the atmosphere through the foot-valve 26, this being the position of valve 26 when the treadle 25 is not depressed. I have not shown the structure of valve 26 or the pipes connecting it to the cylinder as this con-

struction is old and well known and a similar construction is shown in Patents Nos. 1,325,657 and 1,590,433 granted to me Dec. 23, 1919, and June 29, 1926, respectively. 5 With the parts disposed as just described the unbalanced pressure between the pistons forcibly holds the doors closed. Depression of the treadle 25 moves the valve 26 to cut off communication between the space above the large piston and atmosphere and connects that space with the main reservoir whereupon the preponderance of reservoir pressure on the upper sides of pistons 8 and 9 over the pressure on the under side of piston 8 moves the pistons downward and 10 opens the doors, this movement being cushioned by the further compression of the air in space 30 incident to its movement from the large bore to the small bore of the cylinder. Upon release of the treadle 25 valve 26 returns to normal position thus exhausting the space above the large piston to the atmosphere whereupon the constantly maintained reservoir pressure in the space 30 between the pistons moves them upward and 15 through the connecting links and levers closes the doors.

When it is desired to "crack" the doors, i. e. open them partially or wholly and have 20 them remain in such position without keeping the treadle 25 depressed the rod 33 is pushed to the right as viewed in Figure 1 thereby turning the pet cock from the position shown in Figures 1 and 3 to the position 25 shown in Figure 2. This has the effect of blocking reservoir air from space 30 and exhausting the space 30 between the pistons to the atmosphere, and as the treadle 25 is left in its elevated position at this time the 30 space above the large piston 8 is also at atmospheric pressure. It will be understood that the lower end of the cylinder is open and hence there is always atmospheric pressure on the under side of the small piston 9. 35 Hence with the adjustment just described the pistons and doors are free from pressure and as the doors counterbalance each other they may be freely moved by hand to any desired position and will remain in such 40 position until moved by hand power or by restoration of air pressure. To close the doors and restore the parts to position for normal operation by air pressure the rod 33 is pulled to the left as viewed in Figure 1 45 thus restoring valve 32 to the position shown in Figures 1 and 3 and causing the pistons to rise by reason of the unbalanced reservoir pressure in space 30.

One of the objects of this invention is to 50 eliminate the danger resulting from the occurrence of a blow-out when the doors are cracked, that is left partially or wholly open with air pressure cut off from the differential cylinder as above described. In my 55 copending application above referred to I

describe means whereby the pressure in the fire-box resulting from a blow-out, that is from the rupture of one of the boiler plates or tubes with resulting admission of steam to the fire-box, will instantly restore valve 70 32 to the position shown in Figures 1 and 3 and thus cause the doors to close. The invention set forth in this application is for the same purpose and the mechanism is generally similar but embodies the improvement 75 to which the claims are directed.

To accomplish the object described in the preceding paragraph I provide a bell-crank lever 38 pivoted at 40 on a bracket 44, the bell crank being pivotally connected at 37 80 to a rod 36 which at its opposite end is pivotally connected to arm 34 of the pet cock at a point radially outward from the connection of rod 33 therewith. The other end of the bell crank is provided at 39 with a pin which engages a slot 43 in the rod 42 upon the end of which is mounted a pressure member consisting of a plunger or piston 41 having a sliding fit in sleeve 45 which extends through and is welded to 85 boiler plates 46 and 47 thereby forming a cylindrical opening extending from the interior to the exterior of the fire-box. The movement of the plunger 41 in the sleeve 45 may be limited by stops 48, 49, assembly 90 being permitted by welding one of these stops in place after the plunger is inserted in the sleeve and the distance between the stops being sufficient to permit the extent of movement of the plunger necessary to 95 perform its function. In order to dispense with the necessity of welding a stop upon the sleeve at the time of assembling the sleeve and plunger, these parts may be constructed as shown in Figures 5, 6, 7 and 100 8. In this form the flange 48' (Figure 6) is similar to the flange 48 shown in Figure 4 and may be formed when the sleeve 45' is manufactured. The flange at the opposite end of the sleeve 45' is discontinuous, being 105 formed in two opposite segments 70, 71 each of 90 degrees extent shown in Figure 7, which is a section through the sleeve on line A—A of Figure 6. In Figure 8 I show the cross section of the plunger 41' adapted to 110 cooperate with the sleeve shown in Figure 7 and having opposite quadrants 72, 73 of the full diameter of the interior of the sleeve and the intervening quadrants sufficiently less in diameter to just clear 115 the inner edges of the segmental flanges 70, 71 of the sleeve. In assemblage the plunger 41' is first positioned with the projecting quadrants 72, 73 opposite the 120 spaces between the segmental flanges 70, 71 of the sleeve 45', is then moved longitudinally to the inside of the sleeve and then given a quarter turn to bring the projecting quadrants 72, 73 into longitudinal registry 125 130

with the segmental flanges 70, 71 in which latter position the plunger will be held against rotation by its connection with the bell crank lever 48. In the structure forming the subject of the invention claimed herein the length of the slot 43 in plunger-rod 42 is a little less than the length of the movement imparted to pin 39 of the bell-crank when the rod 33 is pushed over to turn valve 32 to the position shown in Figure 2 preparatory to cracking the doors, the effect of which is to permit the valve to be turned freely and without moving plunger 41 until the last part of the movement whereupon pin 39 contacts with the inner end of slot 43 and imparts a short movement to the plunger. I have indicated at 39^a the position of pin 39 when the valve has been given its limit of movement and it will be seen that in order to arrive at this position a slight movement must be imparted to plunger 41 by contact of pin 39 with the end of slot 43. Stop 48 is positioned to permit this movement. When the rod 33 is pulled to the left to restore valve 32 to normal operating position the pin 39 of the bell crank will move freely in the slot 43 until near the end of its movement when it will contact the outer end of slot 43 and move plunger 41 a short distance outward.

In my copending application above referred to I showed two modifications similar generally to the construction above described, but differing in that in one form there was no lost motion between the bell crank and plunger rod 42 and in the other form the amount of lost motion was sufficient to permit operation of valve 32 without imparting any movement whatever to the plunger 41. I have found that it is preferable to permit the major part of the movement of valve 32 to take place without imparting movement to the plunger 41 but that it is desirable to impart a slight degree of movement to the plunger on each actuation of valve 32 in order to eliminate the possibility of the plunger being rendered immovable by the lodgment of coal dust and other foreign matter as might occur if it were permitted to remain stationary relative to the sleeve.

There is also the possibility of the plunger being moved relative to the sleeve by the shocks imposed upon the locomotive in coupling and uncoupling cars. The outward movement of the plunger caused by the pressure of a blow-out in the fire-box moves the bell crank in the direction which restores the pet cock 32 to the position shown in Figures 1 and 3, thus closing the doors and accomplishing the intended purpose. Should a shock upon the locomotive occurring when the doors are cracked cause the plunger to move outward the doors would likewise be moved from cracked to closed position, but

as this is something that would seldom occur and would cause no inconvenience other than the necessity of again cracking the doors no preventive measure is necessary. But if with the doors closed a shock upon the locomotive should cause excess inward movement of the plunger the effect would be to cut off the reservoir air supply from the space 30 between the pistons 8 and 9. If the fireman should then depress the treadle 25 to open the doors the resulting admission of reservoir air to the space above the large piston 8 would drive the pistons downward and open the doors, but with considerable violence due to the absence of air under reservoir pressure in the space 30 between the pistons. Upon releasing the treadle the doors would remain open as the presence of air under reservoir pressure in the space 30 is necessary to effect the closing movement. Under these conditions the structure therefore would become inoperative. In order to prevent the condition described from arising I place the stop 48 at the inner end of sleeve 45 in such a position as to prevent the plunger 41 moving inwardly far enough from the position shown in Figure 4 to turn the bell crank 38 far enough to alter the effective position of the pet cock 32. In order to permit the pet cock 32 to be rotated a short distance without impeding the flow of reservoir air to the space 30 I preferably slightly flare or countersink the ends of the port 60 in the plug of the pet cock as indicated at 61 and 62, shown most clearly in Figure 3.

I claim as my invention:

1. In a boiler fire-box, a door, door operating mechanism comprising means controllable by the operator for opening and closing said door and for retaining said door in open position, means operable by pressure within the fire-box occurring when said door is retained in open position for returning said door to closed position, said last named means comprising a pressure member exposed on one side to the interior of the fire-box and having a lost motion connection with said door operating mechanism, said lost motion connection permitting transmission between the connected members of a part only of their movement.

2. In a boiler fire-box, a door, a fluid pressure cylinder for operating said door, a valve for establishing free communication between said cylinder and the atmosphere in order that said door may be moved to and left in open or partially open position, a pressure member exposed on its inner side to the pressure within the fire-box, a lost motion connection between said pressure member and said valve, the extent of lost motion in said connection being sufficient to permit the major part of the movement of said valve to take place without communicating move-

ment to said pressure member and to limit the transmitted movement to that taking place adjacent the ends of the movement of the valve.

- 5 3. In a boiler fire-box, a door, a fluid pressure cylinder for operating said door, an admission and exhaust valve in said fluid pressure cylinder, an open-ended cylinder extending from the interior to the exterior
10 of said fire-box, a plunger having a sliding fit in said open-ended cylinder, a lost motion connection between said plunger and valve, the extent of lost motion being sufficient to permit only a relatively small part of the
15 movement of said valve to be transmitted to said plunger, outward movement of said plunger under pressure within the fire-box acting to move said valve to the position in which pressure fluid is admitted to said
20 cylinder.

Signed at Chicago, Ill., this 27th day of July, 1929.

JAY G. ROBINSON.
